Application June 14, 1948, Serial No. 146,935

Term of patent 3½ years

(Cl. D80—5)

To all whom it may concern:

Be it known that I, Murray A. Kaufman, a citizen of the United States, residing in New York, county of New York, State of New York, have invented a new, original, and ornamental Design for a Jewelry Display Container or Similar Article, of which the following is a specification, reference being had to the accompanying drawing, forming a part thereof.

Fig. 1 is a perspective view of a jewelry display container or similar article, illustrating my new design;

Fig. 2 is a front elevational view of the jewelry display container or similar article illustrated in Fig. 1; and

Fig. 3 is a side elevational view of the jewelry display container or similar article illustrated in Figs. 1 and 2.

The jewelry display container or similar article shown is substantially oval in plan view and the appearance of the opposite side of Fig. 1 is substantially the same as that disclosed.

I claim:

The ornamental design for a jewelry display container or similar article, substantially as shown and described.

MURRAY A. KAUFMAN.
